UNITED STATES PATENT OFFICE.

AMANDA C. WITT, OF SAN FRANCISCO, CALIFORNIA.

MATERIAL MARKER AND FOLDER.

Application filed June 9, 1921. Serial No. 476,149.

To all whom it may concern:

Be it known that I, AMANDA C. WITT, a citizen of the United States, and a resident of the city and county of San Francisco, 5 State of California, have made a new and useful invention—to wit, Improvements in Material Markers and Folders; and I do hereby declare the following to be a full, clear, concise, and exact description of the 10 same.

This invention relates particularly to an improved material marker and folder.

An object of this invention is to provide an instrument that may be used to mark 15 fabrics and with means thereon for turning an edge of a fabric over into a hem automatically, so that it may be sewed or otherwise secured. A further object of the invention is to provide a device having a graduated scale thereon for the purpose of marking material at any desirable point. A still further object is to provide a device of the character described that will be superior in point of simplicity and inexpensiveness of 20 construction, positiveness of operation, facility and convenience in use and general efficiency. Other objects and advantages will appear as this description progresses.

In this specification and the annexed 30 drawings, the invention is illustrated in the form considered to be the best, but it is to be understood that the invention is not limited to such form, because it may be embodied in other forms, and it is also to be understood that in and by the claims following 35 the description, it is desired to cover the invention in whatsoever form it may be embodied.

In the accompanying one-sheet of drawings,

Figure 1 represents a plan view of a combined material marker and hem guide constructed in accordance with my invention.

Figure 2 represents a side elevation of 45 Figure 1.

Figure 3 represents an end section through Figure 1 on the line 3—3.

In detail the construction illustrated in the drawings, comprises a material marker, 50 generally designated by the numeral 1 and consisting of an elongated sheet of metal or other desirable material bended intermediate its ends, as at 2, to provide a pair of companion members 3 and 4. The garment marker or gauge member as formed is substantially U-shaped in cross-section and each

of the duplicate members 3 and 4 are of any length desirable. An end of the arm 3, as shown in the drawing, is provided with an opening therein through which a piece of chalk, limestone, soap or other marking material 5 is adapted to be passed so that a marking end thereof will lie approximately in contact with the inner face of the lower arm 4. Although I have shown the marking material 5 secured in an opening provided in an end of the arm 3, I do not wish to limit myself to this particular construction as it will be clearly within the purview of this invention to either modify the shape of or provide an auxiliary means for holding said marking material. Along one of its edges the upper face of the gauge arm 3 is provided with graduations 6 of any desirable measurement standard, so that it is possible for an operator to mark material a predetermined distance away from the margin thereof, (without an auxiliary scale) by merely aligning the said margin with the desired graduation.

A hem attachment or hem turner is adapted to be slidably mounted on the arm 3 of the garment marker, and may be moved thereon to any desirable point. The hem attachment comprises an elongated sheet of 85 material 7 preferably the same as that of the garment marker and has an end 8 thereof passed around the arm 3 so as to substantially encircle the same and maintain said hem attachment slidable relative to the 90 member 3. The opposite end (of the hem attachment) is bent under, in an opposite direction to the end 8, at right angles to the main body of material 7 and has the tip 10 thereof ending in a spiral terminus, contiguous to the side edge of the main body 95 7. Thus the edge of material being worked upon, may at the commencement of a sewing operation, be folded over the spirally coiled tip 10, forming a hem that may be sewed or otherwise secured, so that the subsequent 100 hem folding will be done automatically.

The upper face of the end 8 of the hem attachment, is provided with a depression therein forming an embossment 11 on its opposite face which is adapted to register with companion stamped depressions 12 in the upper face of the arm 3 of the material marker. It is thus possible to slide the hem attachment along the garment marker so that the 105 inherent springiness therein will be sufficient to hold it in a semi-permanent position by 110

engagement of the embossment and depressions aforementioned. The frictional engagement between the respective parts is such that one may be moved relative to the other without very great effort on the part of the operator. The arrangement of the combined material marker and hem attachment also makes it possible to hem an edge of material from any desirable point marked on the 10 said material, so that the hem will be uniform and equidistant from the given point.

Having thus described my invention, what I claim and desire to secure by Letters Patent is:

- 15 1. A device such as described comprising, in combination, a U-shaped gauge member, having a piece of marking material removably mounted in an end of one of its arms and graduations along the edge of said one arm; a hemming attachment slidably mounted on said arm and means for maintaining

said gauge member and hemming attachment relatively immovable as regards each other.

2. A device such as described, comprising 25 in combination, a U-shaped gauge member, having a piece of marking material removably mounted in an end of one of its arms and graduations along the edge of said one arm; a hemming attachment slidably mounted 30 on said arm and corresponding embossments and depressions in said hemming attachment and gauge member for maintaining said elements relatively immovable with respect to each other.

35 In testimony whereof, I have hereunto set my hand at San Francisco, California, this 31st day of May, 1921.

AMANDA C. WITT.

In presence of—
LINCOLN V. JOHNSON.
